MECHANICAL CARD GAME APPARATUS

John R. McMahon, Los Angeles, Calif.

Application July 22, 1949, Serial No. 106,203

14 Claims. (Cl. 273—148)

1

This invention relates to games and more particularly to mechanically actuated games having movable groups of cards, or the like, bearing different indicia, wherein the groups are provided in varying series, at least some of which are capable of being aligned or otherwise disposed to form some predetermined pattern whose formation may constitute the winning of the game by the respective player.

A general objective of this invention is to provide a mechanical game, such as the indicated card type, which is novel in construction and arrangement and attractive to persons interested in the playing of mechanical games.

Another object of the invention is to provide a game structure wherein cards, or equivalent carriers of appropriate indicia, are arranged in a novel fashion whereby to dispose different series of cards of different movable groups so that predetermined relationships may be attained by manipulating the cards, or equivalent indicia carriers.

Another object of the invention is to provide a card game, or the like, of the nature above indicated, wherein the mounting means for one group of cards is adapted to be locked when one series of such group has been disposed in a selected playing relationship, the locking of such mounting means serving to unlock mounting means carrying a plurality of other groups of cards. An incidental object is to provide automatic counting means which serves automatically to lock the said mounting means for said plurality of cards following a predetermined number of playing operations. A still further object is to provide means in conjunction with said counting means which renders it possible to distribute the predetermined or allowable number of plays indiscriminately among the mounting means for said plurality of groups of cards, so that each group of said plurality of groups may be actuated as often as desired within the total of said predetermined number.

Another object of the invention is to mount each group of cards, or the equivalent indicia carriers, upon an endless band in a plurality of series extending transversely of said band, so that each band may be mounted upon a blade-like member which supports the endless band and is rotatably mounted about a horizontal axis whereby to present any given series of the respective group in an upwardly facing or other desired playing position. In connection with these objects it will be apparent that selected cards from the conventional so-called playing cards may be

2

used in as many series as required, and it will also be obvious that other types of cards carrying any other types of appropriate related indicia may be used.

5 Other objects of the invention and the various features thereof will become apparent to those skilled in the art upon reference to the following specification and the accompanying drawings wherein the generic invention is illustrated by way of certain embodiments.

In the drawings:

Fig. 1 is an isometric perspective view of a structural arrangement of one form of the invention, wherein substantial portions of an outside casing are broken away to reveal internal arrangements, portions of an internal framework which supports the playing mechanism being also broken away to facilitate the showing;

Fig. 2 is a front elevation of the structure of Fig. 1 with the casing shown fully and in operative position;

Fig. 3 is a fragmentary, vertical section indicated by the line 3—3 of Fig. 1;

Fig. 4 is a front end elevation showing the mechanism at the front of Fig. 1 on an enlarged scale and in different positions from the positions shown in Fig. 1, the forward portion of the casing being removed;

Fig. 5 is a vertical sectional view taken approximately on line 5—5 of Fig. 4;

Fig. 6 is a cross-sectional detail on an enlarged scale taken on the line 6—6 of Fig. 5;

Fig. 7 is a vertical sectional rear view taken on the line 7—7 of Fig. 5;

Fig. 8 is a fragmentary vertical section taken approximately from the line 8—8 of Fig. 7; and

Fig. 9 is a cross section on a small scale of a modified form of rotary carrier member.

The form of the invention illustrated in the drawings comprises: a frame having an upstanding front wall 10, a corresponding rear wall 11 spaced therefrom, a bottom 12 extending between the front and rear walls and side bracing strips 13 suitably disposed and attached to maintain proper spacing of the front and rear walls. There is normally disposed about the framework an outer casing generally indicated at 14 which surrounds the framework except that it is either open at its top or is provided with a transparent top wall 14a through which the cards or other indicia-bearing parts are viewed. The forward end of the casing 14 is ordinarily spaced from the front wall 10 of the frame, as by means of spacer blocks 14b, sufficiently to enclose certain operating mechanism carried forward of the front wall

45

50

55

10, manipulating means, however, being extended through the casing 14 into accessible locations approximately as seen in Fig. 2. The operating means to be concealed by the forward end of the casing 14 is seen in front of the front wall 10 in Fig. 1.

15 Mounted between the front and rear walls 10 and 11 of the framework is a plurality of elongated rotary carrier members 15, 16, 17, and 18 which are successively arranged in parallel relationship, as best seen in Fig. 1 and also indicated in Fig. 4. These carrier members are mounted in the upper portion of the structure so that cards or other indicia-bearing parts will lie only slightly below the transparent top wall 14a in order to facilitate observation by the player. As indicated in Figs. 1, 3, and 4, the carrier members 15, 16, 17, and 18 are in the form of flat, comparatively thin blades of a width to accommodate the width of the cards to be used. However, other forms of carrier members may be employed, such as the square structure 15x shown in Fig. 9, wherein each face is approximately of the width of the cards to be used. The carrier member 15 in the arrangement shown constitutes a primary carrier which is to be manipulated first and then locked, and the carrier members 16, 17, and 18 constitute a secondary group of carriers to be locked when the carrier member 15 is unlocked and to be unlocked for playing purposes when the carrier member 15 is locked, as later to be described.

20 The rearward end of each of the carrier members 15, 16, 17, and 18 is journaled in the rear wall 11 in any appropriate manner, such as by trunnions 19 of Fig. 1. The forward ends of the carrier members 15, 16, 17, and 18 are respectively provided with extensions 15a, 16a, 17a, and 18a which are integral with the carrier members in the form shown and are appropriately journaled in enlarged circular ends 20 of upwardly extending slots 22 provided in the upper portion of the front wall 10 of the frame work. The slots provide for ready installation of the respective carrier members, inasmuch as their extensions may be passed down through the slots 20 after the rearward ends of the carrier members have been moved into the trunnions provided at 19 as above described. In this manner various carrier members are readily disposed in their horizontal operating positions illustrated. With the extensions 15a, 16a, 17a, and 18a in the illustrated positions, the front wall of the outer casing 14 may be readily positioned by causing such extensions to be received in corresponding circular holes in such front wall of the outer casing 14. For the purpose of individual manipulation of the respective carrier members 15, 16, 17, and 18, appropriate knobs 15b, 16b, 17b, and 18b are fitted upon the respective extensions as illustrated in Fig. 2. As seen in Figs. 5 and 7, the middle portions of the forward ends of the carrier members 15, 16, 17, and 18 are locked against rotation, as described below.

25 Upon the respective carrier members 15, 16, 17, and 18 there are mounted horizontally extending endless bands constituting respective card assemblies 25, 26, 27, and 28. Each of these bands is in the form of an endless strip of flexible fabric 30 upon which there are mounted series of cards respectively indicated at 25a, 26a, 27a, and 28a, the cards for each band being arranged in a plurality of transverse series, and the cards of each transverse series being in the form of a row of cards which is adapted to lie along a longi-

tudinal face of the respective carrier member. Adjacent rows of cards of each band are spaced slightly lengthwise of the band as indicated at 31, in order to provide corresponding flexible fabric hinges adapted to fold around the edges of the blade-like carrier members 15, 16, 17, and 18, or around the corners of a polygonal carrier such as the square carrier 15x illustrated in Fig. 9. Thus, as one of the knobs 15b, 16b, 17b, and 18b is turned through 180°, a corresponding row of cards originally disposed face up on the respective carrier is moved downward to one side of the respective carrier, by reason of the folding of the band about the adjacent fabric hinge 31, and the next row of cards on the respective endless band is brought into upwardly facing position where it is supported by the opposite face of the respective carrier member. To prevent swinging of the lower ends of the card assemblies 25, 26, 27, and 28, rods 32 are extended therethrough between the front and rear walls 10 and 11.

20 The carrier members 15, 16, 17, and 18 are adapted to be placed in locked or unlocked condition through the medium of a lock-bar 35 (Figs. 5, 6, and 7) which is disposed upon the inner face of the front wall 10, being pivoted thereon by a pivot pin 36 located at an intermediate position (Figs. 1, 4, and 7), this lock-bar in general extending transversely of the front wall 10. The left end of the lock-bar 35 (right end as viewed in the rear elevation of Fig. 7) is provided with a forward projecting actuator stud 37 (Figs. 1, 4, and 7) which passes through an arcuate slot 38 in the front wall 10 and also through a corresponding arcuate slot 38a (Fig. 2) in the forward wall of the outer casing 14 where its end is accessible for manipulation by the player. When the lock-bar 35 is in the horizontal position shown in broken lines in Fig. 7, the actuator stud 37 lies in the bottoms of the arcuate slots 38 and 38a. Upon release of a trigger 40, as presently to be described, the actuator stud 37 may be manually raised to the tops of the arcuate slots 38 and 38a, thereby rocking the lock-arm 35 upon its pivot pin 36 and thereby moving the lock-arm 35 to the full line position of Fig. 7. When this is done, the longer arm of the lock-bar 35 is withdrawn from its position immediately underlying wings 16c, 17c, and 18c of the carrier members 16, 17, and 18 whereby to unlock said wings by reason of withdrawal of the locking shoulders 42 at the upper edge of the lock-bar 35 from engagement with the respective wings 16c, 17c, and 18c. These shoulders 42 are conveniently formed by providing elongated, sloping notches 43, such notches being directed toward the pivot pin 36 so that the shoulders 42 are disposed at the ends of the notches remote from the pivot pin 36.

25 The lock-bar 35 is normally held in the broken line position of Fig. 7 by means of a spring 44 attached to its end which is adjacent to the primary carrier member 15. It will be apparent that when the lock-bar 35 is in the broken line or locking position with respect to the secondary group of carrier members 16, 17, and 18, such carrier members may not be rotated counterclockwise, as viewed in Figs. 1 and 4 (or clockwise as viewed in Fig. 7) because of engagement of the respective wings 16c, 17c, and 18c with the respective locking shoulders 42. Rotation of the secondary group of carrier members 16, 17, and 18 in the opposite direction will be prevented 30 through the medium of actuating fingers 45 fixed

on the respective extensions of the secondary group of carrier members 16, 17, and 18, as later to be explained. As to the locking of the primary carrier member 15 by the lock-bar 35, this may be accomplished when the lock-bar 35 is in the full line position of Fig. 7, by the provision of a flat locking edge 47 on the upper side of that portion of the lock-bar 35 disposed adjacent the carrier member 15 and underlying the respective wings 15c. Thus, when the corresponding end of the lock-bar 35 is elevated to its full line position, the wings 15c lock in horizontal position against the flat locking edge 47 upon any attempt to rotate the carrier member 15, inasmuch as the portion of the extension 15a which works in the enlarged lower end 20 of the respective slot 22 is broad enough to prevent elevation of the extension 15a upward through such slot 22. It will be appreciated that the extension 15a must be rotated through an arc of 90°, whereby to bring a flattened portion thereof into alignment with the respective slot 22 before such extension may be elevated. The same is true of the other extensions 16a, 17a, and 18a with respect to their slots 22.

When the lock-bar 35 is in the full line position of Fig. 7, it is so held against the tension of the spring 44 by a horizontal latch 48 (Figs. 5, 6, and 7) mounted in the front wall 10 for engagement in the outermost notch 43 as presently to be described.

A preferred form of means for locking the primary carrier member 15 against rotation when the lock-bar 35 is in the full line position of Fig. 7, comprises a locking trigger 50 positioned adjacent to the forward end of the carrier member 15, this trigger 50 being shown in Figs. 7 and 8. It is pivoted to the inner face of the front wall 10 by a pivot 51, and it carries on its lower end a locking pin 52 which is adapted to overlie the adjacent corner of the carrier member 15 (that is, the forward left corner of the carrier member 15 as seen in Fig. 4). This locking trigger 50 is moved about the pivot 51 into its full line or locking position of Fig. 7 by means of a cam face 53 provided on an upstanding portion 54 of the lock-bar 35 adjacent to the end in which the actuator stud 37 is fixed. A stop pin 55 may be employed to limit swinging movement of the trigger 50 beyond locking position, and it may be loaded by a spring 56 to restore it to non-locking position when the lock-bar 35 is in its horizontal, broken line position and there held by the tension spring 44. When this locking means is used, the wings 15c may be omitted.

As has been previously indicated, each carrier of the group of secondary carrier members 16, 17, and 18 is to be actuated by counterclockwise rotation. The primary carrier member 15 is to be actuated by clockwise rotation. For the purpose of insuring this clockwise rotation, there is fixed upon the extension 15a of the carrier member 15, forward of the front wall 10, a ratchet or check member 60 which is double ended and provides shoulders 61 adapted to be engaged by a dog 62 on the previously mentioned trigger 40 which is pivoted at 63 in a position to dispose a stop-arm 64 thereof in the path of the actuator stud 37. As indicated in both Figs. 1 and 4, the trigger 40 is loaded by a spring 65 which urges it into a position against a stop pin 64a to block the stud 37. In order to provide a checking effect as the primary carrier member 15 is rotated each end of the check member 60 is provided opposite the respective shoulders 61 with operating

fingers 66 which, when rotated clockwise, engage the dog 62 to withdraw the stop-arm 64 from the stud-blocking position, against the tension of the spring 65, until the dog 62 is disengaged by the respective finger 66. This arrangement in effect provides a notch 67 at each end of the check member 60 between the corresponding lock shoulder 61 and operating finger 66. As a consequence of this arrangement the carrier member 15 cannot be rotated counterclockwise because of the locking function performed by the dog 62 and the respective lock shoulders 61. This structural arrangement also provides for actuation of the trigger 40 by the respective operating finger 66 to withdraw the stop-arm 64 from stud-blocking position upon rotary movement of the corresponding knob 15b, so that the stud 37 may be raised and rock the lock-arm 35 against the spring 44 and about its pivot pin 36 to lower the opposite end of the lock-bar 35 and permit the previously mentioned latch 48 to drop into the outermost notch 43 and hold the lock bar 35 in the full line position of Fig. 7 against the tension of the spring 44 and unlock the group of secondary carrier members 16, 17, and 18.

Regarding the functioning of the latch 48, which engages in the outermost notch 43 to retain the lock-bar 35 in the full line position of Fig. 7 where it unlocks the secondary carrier members 16, 17, and 18, this latch is pivoted on the front wall 10 by a substantially vertical pivot 70 carried by the front wall either directly or through the medium of a cylindrical block 71 which is fixed to the outer face of the front wall 10 and serves also to support a rotary ratchet wheel 72. The front wall 10 is provided with a transverse slot 74 through which one end of the latch 48 projects and in which it works. The latch 48 is loaded by spring 75 which urges it toward the latching position shown in Fig. 6. A toe 76 is provided at one corner of the latch 48 to limit its movement under the influence of the spring 75. The latch 48 is adapted to be withdrawn from the locking position of Figs. 6 and 7 by means of a stud or other appropriate trip 78 carried on the back face of the ratchet wheel 72, so that, when the ratchet wheel 72 has been moved through a complete rotation, the trip 78 engages an adjacent edge portion 79 of the latch 48 to swing it about the pivot 70 and disengage the upper face portion of the respective notch 43 at the outer end of the lock-bar 35 whereby to permit the spring 44 to return the lock-bar 35 to the broken line position of Fig. 7 and lock the secondary carrier members 16, 17, and 18 against counterclockwise rotation.

As best indicated in Figs. 1 and 4, the ratchet wheel 72 is advanced in a clockwise direction by means of a spring loaded ratchet feed finger 80 which is pivoted at 81 upon an outer face portion of a reciprocating feeder-arm 82 carried in appropriate retainers 82a which permit the necessary reciprocating movement. The feeder-arm 82 is adapted to be advanced by the previously mentioned actuating fingers 45 fixed on the extensions 16a, 17a, and 18a of the secondary carrier members 16, 17, and 18. A spring 83, one end of which is attached to the front wall 10 and the other end which is attached to the feeder-arm 82 serves to return the arm 82 after each excursion effected by any one of the actuating fingers 45. It will be noted that each actuating finger 45 is double ended so that it may throw the feeder-arm 82 at each half revolution,

The feeder-arm 82 is provided with a shoulder 84 for each double actuating finger 45, one of these shoulders being conveniently provided by the left end of the bar 82, the other shoulders 84 being provided by forming notches 85 in the upper edge of the arm 82 large enough to permit the necessary travel of the respective actuating fingers 45. To prevent reverse rotation of the ratchet wheel 72 by frictional drag of the feed finger 88 as the latter is returned with the bar 82 by the spring 83, a stop dog 86 held by a stud 88 on the front wall 10 is employed. This dog 86 may be of any yielding, sufficiently stiff material such as a leaf spring or a stiff leather strip engageable with the ratchet teeth.

Since the feeder-arm 82 may be advanced by any one of the actuating fingers 45 as they are moved in connection with shifting of the various card rows of the three secondary card assemblies 26, 27, and 28, it is obvious that all of the plays made with the secondary card assemblies 26, 27, and 28 combined are additively registered by the feeder-arm 82 upon the ratchet wheel 72. Thus, when the number of plays of these three secondary card assemblies reaches a predetermined total, for example fifteen, the stud trip 78 withdraws the latch 48 and releases the lock-bar 35 thereby preventing further rotation of the secondary carrier members 16, 17, and 18 and concluding the game.

When the lock-bar 35 has been released so that the spring 44 returns it from the full line position of Fig. 7 to the broken line position, thereby locking the carrier members 15, 16, 17, and 18 by the shoulders 42 on the upper edge of the lock-bar 35, the opposite end of the lock-bar 35 is moved downward to withdraw the flat locking edge 47 from engagement with the wings 15c of the primary carrier member 15. Such movement also releases the locking trigger 50 so that its spring 56 returns it to non-operative position and thus moves the locking pin 52 out of the path of the adjacent corner portion of the carrier member 15. Incidentally, when the respective end of the lock-bar 35 is drawn down by the spring 44, thereby drawing downward the actuator stud 37, the spring-loaded trigger 40 yields against its spring 65 to permit the stud 37 to move into the bottom of the arcuate slots 38 and 38a. Under these conditions the parts are reset to commence the game anew.

Operation

The operation of the apparatus has, in general, been described along with the above description of the structural features. In brief, the game may be played by starting with the parts in the positions shown in Fig. 1. The knob 15b is rotated clockwise to rotate the primary carrier 15 and bring into horizontal position any one of the series or rows of cards 25a of the primary card assembly 25 that may meet the fancy of the player. He then rotates the knob 15b through a short arc until the operating finger 66 which is in engagement with the dog 62 of the trigger 40, moves the latter sufficiently to withdraw the stop-arm 64 of the trigger 40 from the path of the actuator stud 37. The outer, exposed end of the actuator stud 37 is then lifted by the player into the upper portion of the slots 38 and 38a, thereby swinging the lock-bar 35 about its pivot pin 36 against the tension of the spring 44 and causing the opposite end of the lock-bar 35 to be depressed until the latch 48 adjacent to the sprocket wheel 72 is actuated by

its spring 75 to engage over the adjacent upper edge portion of the lock-bar 35, which edge portion in the form shown happens to be at the outermost notch 43. The lock-bar 35 is now retained in the full line position of Fig. 7, thereby unlocking the wings 16c, 17c, and 18c of the secondary carrier members 16, 17, and 18, while locking the wings 15c and the primary carrier member 15 by the means shown at the right of Fig. 7, as above described. Under these conditions the primary carrier member 15 may be no longer rotated but any one or all of the secondary carrier members 16, 17, and 18 may be rotated counterclockwise through any number of plays up to the predetermined total represented by the ratchet teeth in the ratchet wheel 72. As previously indicated, each 180° of counterclockwise rotation of each secondary carrier member 16, 17, and 18 produces one reciprocation of the feeder-arm 82 through the medium of the respective actuating finger 45. When the various cards 25a, 26a, 27a, and 28a of the several card assemblies 25, 26, 27, and 28 have been brought into the horizontal positions in an order required by the rules of the game without prior release of the latch 48, the game is considered won. However, if such a card order has not been attained within the number of plays provided by the ratchet wheel 72, and before the stud trip 78 on the inner face of the ratchet wheel 72 trips the latch 48 and releases the lock-bar 35, the game is lost.

The cards 25a, 26a, 27a, and 28a of the various assemblies may be of any type preferred. As generally indicated in Fig. 1, they may be in the form of various arrangements of aces, kings, queens, and jacks of the conventional playing card type. Thus, each row facing upward upon the carrier members 15, 16, 17, and 18 would contain an ace, king, queen, and jack of any suit or of mixed suits. In order to win the game, the rules may provide either that no two cards of any suit or denomination appear in any horizontal row, or that somewhere on each of the card assemblies 25, 26, 27, and 28 there be some required arrangement in the vertical rows of cards as they appear in viewing position on the respective carrier members. For example, as shown on carrier member 15, the order is ace, king, jack, queen. To win, either there would have to be no corresponding suit nor ace, king, jack, or queen on the other carriers in any one horizontal row, or some specified arrangement would have had to develop. It is apparent that any other type of cards than the conventional playing cards may be used. For example, various card combinations representative of animals, flowers, trees, or fruits might be used for educational purposes. It will be obvious, of course, that the actuator finger 37 may be under the control of a coin actuated mechanism if desired.

Inasmuch as modifications of the generic invention herein disclosed will occur to those skilled in this art, it is intended to protect all such forms as fall within the scope of the patent claims.

I claim as my invention:

1. A mechanical game comprising in combination: a plurality of laterally spaced elongated rotary carrier members arranged in substantially parallel relation and disposed on laterally spaced horizontal axes of rotation; a flexible elongated looped member individually carried by each of said carrier members; means to rotate said carrier members selectively; a plurality of series of

9

aligned indicia-bearing parts disposed upon each looped member, the indicia-bearing parts in each series being aligned, and said series being arranged in approximate parallelism with one another, each rotary carrier member having means positioned to present to view each series of aligned indicia-bearing parts, whereby plural series presented in substantially parallel relation by said carrier members may be viewed simultaneously and indicia thereon compared; a framework in which said carrier members are mounted to rotate upon said horizontal axes; first locking means to lock one of said carrier members; second locking means to lock others of said carrier members; a movable device between said first and second locking means to move one thereof into locking position while withdrawing the other to unlocking position; and releasable latch means to retain said device in position holding said other locking means withdrawn.

2. A combination as in claim 1 including: advancing means movable on said framework; cooperating means on certain of said carrier members and said advancing means for actuation of said advancing means upon each actuation of said certain of said carrier members; progressively movable releasing means mounted on said framework to engage and release said latch means upon predetermined movement; and a drive connection between said advancing means and said releasing means to advance the latter by increments through said predetermined movement by successive actuations of said advancing means.

3. A combination as in claim 1 wherein said first locking means is a latch means located adjacent and controlled by said lock device and movably mounted to move into the path of rotation of said one of said carrier members upon movement of said lock device.

4. A combination as in 1 wherein said second locking means includes shoulders formed on said lock device and means on the respective carrier members to engage and be locked against rotation by said shoulders, when said lock device is released.

5. In combination in a mechanical game: a primary rotary carrier; a plurality of secondary rotary carriers; a framework on which said carriers are mounted adjacent one another and are journaled to rotate; a series of indicia-bearing parts mounted upon each of said carriers for movement selectively into position to be simultaneously viewed and compared; first locking means for locking said primary carrier against rotary movement; second locking means for locking said secondary carriers against rotary movement; means interconnecting said first locking means and said second locking means to move one locking means into locking position while withdrawing the other locking means from locking position; means to urge said locking means to one of their positions; and latch means engageable with said interconnecting means to retain said locking means in the other of their positions.

6. In combination in a mechanical game: a primary rotary carrier; a plurality of secondary rotary carriers; a framework on which said carriers are mounted adjacent one another and are journaled to rotate; a series of indicia-bearing parts mounted upon each of said carriers for movement selectively into position to be simultaneously viewed and compared; first locking means for locking said primary carrier against

10

rotary movement; second locking means for locking said secondary carriers against rotary movement; means interconnecting said first locking means and said second locking means to move one locking means into locking position while withdrawing the other locking means from locking position; means to urge said locking means to one of their positions; latch means engageable with said interconnecting means to retain said locking means in the other of their positions; trip means to release said latch means; and advancing means actuatable by movements of each of said secondary carriers to actuate said trip means upon a predetermined number of movements of said advancing means.

7. A combination as in claim 6 wherein said advancing means includes: a reciprocable bar disposed on said framework adjacent said secondary carriers; means on said secondary carriers to engage and move said bar upon rotation of said carriers; and means on said bar to engage and move said trip means.

8. A combination as in claim 7 wherein: said trip means includes a ratchet wheel having a member to engage and actuate said latch means; said bar carries a dog engageable with said ratchet wheel to move said wheel on each advancement of said reciprocable bar; and means is provided for retracting said bar following each advancement thereof.

9. In combination in a mechanical game: a primary carrier; a plurality of secondary carriers; a framework on which said carriers are movably mounted adjacent one another; means to move said carriers selectively; a series of indicia-bearing parts disposed upon each of said carriers for movement of indicia by the various carriers into viewing position; a lock-bar movably mounted on said frame adjacent said carriers; first locking means carried by said lock-bar adjacent said primary carrier to lock the latter when said lock-bar is in one position; second locking means carried by said lock-bar to lock said secondary carriers when said lock-bar is in another position; means to move said lock-bar to one of said positions; means to move said lock-bar to the other of said positions; latch means to hold said lock-bar in one of such positions; and trip means actuatable by movement of certain of said carriers to trip said latch means upon predetermined movements of such carriers.

10. A combination as in claim 9 wherein said trip means includes advancing means carried by said framework adjacent said secondary carriers, and wherein certain of said carriers have actuating means to engage and move said advancing means upon movement of said secondary carriers.

11. A combination as in claim 10 wherein said advancing means includes: a reciprocable bar provided with engaging means; and progressively movable means to be engaged and moved by said engaging means upon successive advances of said advancing means, said latch releasing means being operated by said progressively movable means, the combination including means to return said reciprocable bar after each advancement.

12. A combination as in claim 11 wherein said progressively movable means is a ratchet wheel and said engaging means on said reciprocable bar is a dog engaging the teeth of the ratchet wheel.

13. A combination as in claim 9 wherein said carriers are elongated and each carrier carries

11

a plurality of rows of indicia-bearing parts, such parts of each row being aligned to lie lengthwise of the respective carriers, whereby the various rows faced in the same direction on the various carriers may be viewed and compared simultaneously.

14. A mechanical game comprising in combination: a plurality of laterally spaced elongated rotary carrier members arranged in substantially parallel relation and disposed on laterally spaced horizontal axes of rotation; a flexible elongated looped member individually carried by each of said carrier members; means to rotate said carrier members selectively; a plurality of series of aligned indicia-bearing parts disposed upon each looped member, the indicia-bearing parts in each series being aligned, and said series being arranged in approximate parallelism with one another, each rotary carrier member having means positioned to present to view each series of aligned indicia-bearing parts, whereby plural series presented in substantially parallel relation by said carrier members may be viewed simultaneously and indicia thereon compared; a framework in which said carrier members are 25 rotatably mounted; means on said members to

rotate the latter; first locking means to lock one of said members; second locking means for locking the remainder of said members; and means interconnecting said first and second locking means to release one thereof while rendering the other effective, and including trip means positioned adjacent said locking means for normally holding the latter ineffective and releasable to render said second locking means effective upon a predetermined number of actuations of the carrier means controlled thereby.

JOHN R. McMAHON.
